UNITED STATES PATENT OFFICE

1,966,689

FILE CABINET DRAWER

Joseph C. Seyl, Evanston, Ill.

Application February 5, 1934, Serial No. 709,710

10 Claims. (Cl. 129—16)

The invention relates generally to file cabinet drawers for retaining or holding in a substantially vertical position papers, records, files and like matter. More particularly, the invention relates to that type of filing cabinet drawer which has a longitudinal channel in the central portion of the bottom thereof and a longitudinal rod in the channel, and embodies a plurality of upstanding partitions which serve to separate the papers into groups, are free to swing backwards and forwards to a limited extent in order to facilitate access to the papers and are connected to the rod so that they may be shifted bodily throughout substantially the entire length of the drawer so as to vary the space between them.

One object of the invention is to provide a filing cabinet drawer of this type in which the connections between the partitions and the rod whereby the partitions are shiftable bodily substantially throughout the entire length of the drawer comprise (1) blocks which are slidably mounted on the rod and have holes in the sides thereof, and (2) arms which are connected to, and depend from, the lower portions of the partitions and have inturned lower ends which fit in the holes in the blocks and form pivotal connections between the blocks and the partitions so that the latter are free to swing forwardly and backwardly in the drawer.

Another object of the invention is to provide a filing cabinet drawer of the last mentioned character in which the blocks have pairs of stop lugs at the sides thereof which coact with the depending arms on the bottom portions of the partitions in order to limit forward and backward swinging movement of the partitions in the drawer.

Another object of the invention is to provide a filing cabinet drawer of the type and character under consideration in which the partitions are provided adjacent to the arms with depending dogs and the partitions are releasably locked against bodily shift lengthwise of the drawer by means of a rack which is disposed in, and extends lengthwise of, the channel in the bottom of the drawer and is mounted to swing vertically into interlocked relation with the dogs.

A further object of the invention is to provide a filing cabinet drawer of the type and character last mentioned in which the vertically swinging rack in the channel in the drawer bottom is controlled as far as swinging thereof into and out of interlocked relation with the dogs is concerned, by means of an arm which is connected to and extends upwardly from the front end of the rack

and fits slidably against the inner face of the front of the drawer.

A still further object of the invention is to provide a filing cabinet drawer which is generally of new and improved construction and may be manufactured at a comparatively low cost.

Other objects of the invention and the various advantages and characteristics of the present construction of filing cabinet drawer will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary perspective of a filing cabinet drawer embodying the invention;

Figure 2 is a fragmentary perspective of the rack which is mounted in the channel in the drawer bottom to swing vertically into and out of interlocked relation with the dogs on the bottom portion of the partitions;

Figure 3 is a vertical, transverse section of the drawer, illustrating in detail the construction and arrangement of the dogs and the arms for connecting the partitions pivotally to the blocks on the rod;

Figure 4 is a vertical, longitudinal section taken on the line 4—4 of Figure 3 and showing in detail the manner in which the depending arms on the partitions are pivotally connected to the blocks and coact with the stop lugs on the sides of the blocks in order to limit forward and backward swinging of the partitions;

Figure 5 is a vertical, longitudinal section taken on the line 5—5 of Figure 3;

Figure 6 is a perspective of one of the blocks whereby the partitions are connected to the rod so that they are shiftable bodily substantially throughout the entire length of the drawer; and

Figure 7 is a bottom view of the block of Figure 6 disclosing the manner in which the latter is connected slidably to the rod.

The drawer which forms the subject matter of the invention is designed for association with a cabinet or analogous supporting structure (not shown) and serves to retain in a substantially vertical position papers, records, files and like matter. It is adapted to slide horizontally in the filing cabinet or supporting structure and comprises a bottom 8, sides 9, a front 10 and a back 11.

as well as a plurality of upstanding partitions 12 for separating the papers in the drawer, as is well understood in the art. The bottom 8 of the drawer is rectangular and is deflected or shaped centrally so that it embodies a longitudinally extending channel 13. The latter extends throughout the entire length of the bottom 8, as shown in Figure 1 of the drawings, and is closed at the back end thereof by means of a flange 14 and at the front end thereof by means of a flange 15. The flange 14 is spaced slightly forwards of the back 11 and is formed integrally with, and is bent upwardly from, the rear end portion of the part of the drawer bottom which forms the bottom of the channel 13. The flange 15 is spaced slightly rearwards of the front 10 and is formed integrally with, and is bent upwardly from, the front end portion of the part of the bottom 8 which forms the bottom of the channel 13. The sides 9 are formed integrally with, and project upwardly from, the side margins of the drawer bottom 8, and together with the bottom, front and back of the drawer, form a filing compartment. The front 10 closes the front of this compartment. It is of greater height than the sides 9 and back 11 and is connected to the front ends of the sides 9 by means of brackets 16. The latter extend rearwardly from the side margins of the front 10 and are welded or otherwise secured to the outer faces of the sides 9. The back 11 closes the back end of the filing compartment and is connected to the rear ends of the sides 9 by flanges 17. The latter are formed integrally with, and project forwardly from, the side margins of the back 11 and are welded or otherwise secured to the inner faces of the sides 9.

The partitions 12 are formed of sheet metal and are substantially the same in width as the bottom 8 so that the spaces between them do not communicate with each other and the papers or material cannot slip from one space to the other. The top margins of the partitions are extended so as to project upwardly of the sides 9 of the drawer. In order to facilitate access to the papers between the partitions and to provide for an adjustment of the space between the partitions, the partitions are mounted so that they are free to swing backwards and forwards in the drawer to a limited extent and so that they are bodily shiftable throughout substantially the entire length of the drawer. The mount whereby the partitions are supported in this manner comprises a rod 18 and a plurality of blocks 19. The rod 18 is located at one side of, and extends lengthwise in, the channel 13 in the drawer bottom 8 and is spaced slightly above the bottom part of the channel. The rear end of the rod 18 extends through an aperture 20 in the flange 14 and is provided with a cotter pin 21 which abuts against this flange and prevents forward movement of the rod in the channel. The front end of the rod extends through an aperture 22 in the upstanding flange 15 at the front end of the channel 13 and is provided with a cotter pin 23 whereby it is held against rearward movement in the channel. The blocks 19 engage the bottom part of the channel 13 and have holes 24 therethrough through which the rod 18 extends so that they are slidable in the channel from one end thereof to the other. In addition to the rod 18 and the blocks 19, the mount whereby the partitions 12 are supported so that they are free to swing forwards and backwards in the drawer to a limited extent and to be shifted bodily throughout substantially the entire length of the drawer

comprises pairs of arms 25. There is one pair of arms for each partition and these arms are welded or otherwise secured to the back faces of the partitions so that they extend vertically and the lower ends thereof project beyond the bottom margins of the partitions and into the channel 13. Sheet metal plates 26 are secured to the back faces of the partitions 12 and extend around and house the central and upper portions of the arms 25. These plates are provided with side flanges 27 whereby they are held in spaced relation with respect to the partitions. The flanges 27 fit against the back faces of the partitions and are riveted or otherwise secured in place. The lower ends of the arms 25 are bent inwardly and fit in holes 28 in the sides of the blocks 19 so as to form pivotal connections between the blocks and the partitions whereby the latter are held or confined in the drawer to forward and rearward swinging movement. Lengthwise adjustment of the partitions in the drawer is effected by sliding them to or from the front of the drawer through the medium of the blocks 19 on the rod 18. In order to limit forward and rearward swinging of the partitions, the blocks 19 are provided at the sides thereof with pairs of oppositely facing stop lugs 29. These lugs, as shown in the drawings, are disposed on opposite sides of the arms 25 and have oppositely facing, upwardly divergent faces 30 which coat with the lower ends of the arms 25 to limit forward and rearward swinging of the partitions in the drawer. The lugs are integral with the blocks 19 and are preferably formed by recessing or cutting away the sides of the blocks. To assist the stop lugs 29 in limiting forward and rearward swinging movement of the partitions, horizontally extending rods 31 are provided. These rods are secured to the top margins of the partitions by bending the latter into tubular form and are of such length that the ends thereof project beyond the side edges of the partitions and rest on the top edges of the sides 9. The partitions 12 are releasably locked or held against shift lengthwise of the drawer by means of a sheet metal rack 32 and a dog 33 on each of the partitions. The rack 32 is disposed in the channel 13 in the drawer bottom 8 and is located at one side of the rod 18. It extends from one end of the channel to the other and is provided with a series of upstanding teeth 34 along one margin thereof. The dogs 33 are mounted for vertical sliding movement between the plates 26 and the rear faces of the partitions 12. The upper ends of the dogs are provided with laterally extending ears 35 which overlie the adjoining arms 25 and coat with the upper ends of the latter so as to limit downward movement of the dogs. Screws or bolts 36 extend through the center portions of the partitions and form stops for limiting upward sliding movement of the dogs. The lower ends of the dogs project beneath the bottom portions of the partitions and into the channel 13 and are designed to interlock with the teeth 34 of the rack so as to effect the desired locking of the partitions in their assigned positions. The spacing of the teeth 34 is such that when the partitions are locked in place they are free to swing forwards and backwards to the extent permitted by the stop lugs 29 at the sides of the blocks 19. The rack 32 is supported by way of a shaft 37 so that it may be swung downwardly in order to disengage the teeth 34 from the dogs 33 and thus release the partitions for shift lengthwise of the drawer. The shaft 37 is rigidly secured in a tube 38 along the side margin of the rack that is opposite the teeth 34. The

rear end of the shaft projects beyond the rack and is journalled in a hole 39 in a plate 40 on the upstanding flange 14. The front end of the shaft 37 projects beyond the front end of the rack and 5 is journalled in a hole 41 in a bearing plate 42. The latter, as shown in Figure 1 of the drawings, is disposed at the front end of the channel 13 and is secured against the inner face of the upstanding flange 15. The rack 32 is swung into 10 and out of interlocked relation with the dogs 33 by means of an arm 43. The latter is connected in any suitable manner to the front end of the shaft 37 and extends upwardly along the rear face of the front of the drawer. A knob 44 is 15 attached to the upper end of the arm 43 and serves as a handle whereby the arm may be swung sidewise with respect to the drawer for rack-swinging purposes. The arm 43 is preferably of such length that the knob 44 is disposed adjacent 20 the upper or top margin of the drawer front 10 and hence is readily accessible and does not interfere with papers that are filed in the drawer. A spring clip 45 is attached to the inner face of the drawer front 10 and is adapted to hold the 25 arm 43 in the position that it assumes when the rack 32 is in its operative position, that is, the position wherein the teeth 34 are interlocked with the dogs 33 on the partitions. The entrance end of the clip is flared outwardly so as to facilitate 30 shift of the arm into locked relation with respect to the clip. When it is desired to shift the partitions 12 lengthwise of the drawer, the arm 43 is released from the clip 45 and is then swung to one side so as to swing the rack 32 downwardly 35 and disengage the teeth 34 from the dogs 33 (see dotted line position of rack in Figure 3). When the teeth of the rack are disengaged from the dogs, the partitions are free so that they may be slid either frontwards or backwards. When the 40 partitions are positioned in the manner desired, the arm 43 is swung in the opposite direction and into locked relation with the clip 45. This swinging of the arm results in upward swinging of the rack and interlocking of the teeth 34 and the dogs 33. When the dogs and teeth of the rack 45 are in interlocked position, the partitions are held against lengthwise movement in the drawer, although they are free to swing to a limited extent forwards and backwards. By virtue of the fact that the dogs 33 are vertically slidable, upward swinging of the rack is not precluded when any of the dogs are disposed over one of the teeth 34. The bottom edges of the partitions, as shown in the drawings, rest on the top face of the bottom 50 of the drawer.

The herein described filing cabinet drawer consists of but a small number of parts and therefore may be manufactured at a low and reasonable cost. It is exceedingly simple as far as construction is concerned, and comprehends novel means for supporting the partitions for limited backward and forward swinging and movement lengthwise of the drawer, and for locking the partitions in their different assigned positions in the drawer.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In combination, a filing cabinet drawer having a longitudinal channel in the bottom thereof, a rod disposed in and extending longitudinally

of the channel, a block slidably mounted on the rod for movement lengthwise of the drawer, a partition extending substantially vertically in the drawer and having a depending arm at the lower margin thereof projecting into the channel and connected pivotally to the block so that the partition is free to swing forwards and backwards and is adjustable longitudinally of the drawer by sliding of the block on the rod, and means associated with the block and coacting with the arm for limiting swinging movement of the partition. 80

2. In combination, a filing cabinet drawer having a longitudinal channel in the bottom thereof, a rod disposed in and extending longitudinally of the channel, a block slidably mounted on the rod for movement lengthwise of the drawer, a partition extending substantially vertically in the drawer and having a depending arm at the lower margin thereof projecting into the channel and connected pivotally to the block so that the partition is free to swing forwards and backwards and is adjustable longitudinally of the drawer by sliding of the block on the rod, and a pair of stop lugs on the block positioned on opposite sides of the arm and coacting with the latter to limit 85 swinging of the partition. 90

3. In combination, a filing cabinet drawer having a longitudinal channel in the bottom thereof, a rod disposed in and extending longitudinally of the channel, a block slidably mounted on the rod for movement lengthwise of the drawer and having a hole in one side thereof, a partition extending substantially vertically in the drawer and provided at the lower portion thereof with a depending arm projecting into the channel and 105 having an inturned part fitting in the hole in the block and forming a pivotal connection between the block and the partition whereby the partition is free to swing forwards and backwards in the drawer and is adjustable longitudinally of 110 the drawer by sliding of the block on the rod, and means for limiting swinging movement of the partition. 115

4. In combination, a filing cabinet drawer having a longitudinal channel in the bottom thereof, 120 a rod disposed in and extending longitudinally of the channel, a block slidably mounted on the rod for movement lengthwise of the drawer and having a hole in one side thereof, a partition extending substantially vertically in the drawer 125 and provided at the lower portion thereof with a depending arm projecting into the channel and having an inturned part fitting in the hole in the block and forming a pivotal connection between the block and the partition whereby the 130 partition is free to swing forwards and backwards in the drawer and is adjustable longitudinally of the drawer by sliding of the block on the rod, and a pair of stop lugs connected to the block on opposite sides of the hole and coacting with 135 the arm to limit swinging movement of the partition.

5. In combination, a filing cabinet drawer having a longitudinal channel in the bottom thereof, a rod disposed in and extending longitudinally 140 of the channel, a block slidably mounted on the rod for movement lengthwise of the drawer and having holes in the sides thereof, a partition extending substantially vertically in the drawer and provided at the lower portion thereof with a pair 145 of laterally spaced, depending arms extending into the channel and on opposite sides of the block and having inturned lower ends fitting within the holes in the block sides respectively and forming a pivotal connection between the 150

block and the partition whereby the partition is free to swing forwards and backwards in the drawer and is adjustable longitudinally of the drawer by sliding of the block on the rod, and means for limiting swinging movement of the partition.

6. In combination, a filing cabinet drawer having a longitudinal channel in the bottom thereof, a rod disposed in and extending longitudinally of the channel, a block slidably mounted on the rod for movement lengthwise of the drawer and having holes in the sides thereof, a partition extending substantially vertically in the drawer and provided at the lower portion thereof with a pair of laterally spaced, depending arms extending into the channel and on opposite sides of the block and having inturned lower ends fitting within the holes in the block sides respectively and forming a pivotal connection between the block and the partition whereby the partition is free to swing forwards and backwards in the drawer and is adjustable longitudinally of the drawer by sliding of the block on the rod, and pairs of stop lugs on the sides of the block arranged in straddled relation with respect to the holes and coacting with the arms to limit swinging movement of the partition.

7. In combination, a filing cabinet drawer, a partition extending substantially vertically in the drawer and mounted so that it is adjustable longitudinally of the drawer, and means for releasably locking the partition in different longitudinal positions in the drawer comprising a dog on the partition and a rack extending lengthwise of the drawer and pivoted to swing vertically into and out of interlocked relation with the dog.

8. In combination, a filing cabinet drawer, a

partition extending substantially vertically in the drawer and mounted so that it is adjustable longitudinally of the drawer, and means for releasably locking the partition in different longitudinal positions in the drawer comprising a depending dog on the partition and a rack disposed in and extending lengthwise of the drawer provided with upwardly extending teeth and pivoted so as to swing vertically in order to bring the teeth into and out of interlocked relation with the dog.

9. In combination, a filing cabinet drawer having a longitudinal channel in the bottom thereof, a partition extending substantially vertically in the drawer and mounted so that it is bodily adjustable longitudinally of the drawer, and means for releasably retaining the partition in its different adjusted positions in the drawer comprising a dog depending from the bottom portion of the partition and extending into the channel and an elongated rack disposed in and lengthwise of the channel and pivoted to swing vertically into and out of interlocked relation with the dog.

10. In combination, a filing cabinet drawer, a partition extending substantially vertically in the drawer and mounted so that it is free to swing forwards and backwards to a limited extent and is adjustable longitudinally of the drawer, and means for locking the partition in its various adjusted positions and at the same time permitting of limited swinging movement of said partition comprising a dog on the partition and a rack disposed in and extending lengthwise of the drawer and pivoted to swing on a horizontal, longitudinal axis into and out of interlocked relation with the dog.
